2,529,004

POWDER APPLICATOR HAVING A POWDER-RECEIVING SPOUT AND A RECESSED OUTLET ACCOMMODATING A TOOTHBRUSH

Virgil D. Eley, Philadelphia, Pa.

Application February 1, 1946, Serial No. 644,751

3 Claims. (Cl. 222—48)

1

This invention relates to a small unique applicator for powder and the like, and particularly a container that may be held in the palm of the hand for holding tooth powder, wherein the bristles of a tooth brush may be inserted through an opening therein for contacting and picking up the powder.

The usual containers for tooth powder are formed with an opening in the end or in the side adjacent the end and the powder is poured through this opening on to the brush and as the powder does not flow readily but runs out in uneven, jerky, impulses there is considerable waste. This invention contemplates a powder container into which a tooth brush is placed to contact and pick up the powder, instead of pouring the powder thereon.

The container is of sufficient size to hold several charges of powder, wherein it may be used for several days without refilling. It is, therefore useful for week-end trips and the like.

The container of this invention is provided with a filling spout, that may be inserted in the discharge opening of a tooth powder container, so that powder may be poured through the spout into the container. The container is also provided with a tooth brush opening and an internal cylinder, having an opening adapted to register with the spout for filling, at which time the tooth brush opening is closed and then adapted to be turned to close the spout and register with the tooth brush opening when it is desired to insert a tooth brush. The internal cylinder is also adapted to be turned to close both openings when the device is not in use.

In containers of this type the contents may become damp and, if the powder is permitted to remain in the container for some time, it may cake in the corners and, for this reason, the container is readily opened for cleaning.

The purpose of this invention is to facilitate the application of tooth powder to a tooth brush by holding the powder in a substantially closed container in the palm of the hand and dipping the tooth brush in the powder, whereby only the amount of powder required is taken up by the brush and waste is eliminated.

To accomplish this end the container should have a filling opening and also an opening through which the powder may be used, and as the opening of an inner cylinder or closure must be adapted to register with either opening, it is advisable to provide indicating means for locating the inner cylinder in the open and closed positions. The inner cylinder is, there-

fore, provided with a projection adapted to snap into recesses in the container to definitely indicate the closed position, and additional recesses may also be provided for indicating the filling and using positions.

The object of the invention is to provide a relatively small cylindrical container, having an elongated opening of sufficient size to accommodate the bristles of a tooth brush, which may be filled or partly filled with tooth powder that may be picked up by a brush inserted in the opening, and which is provided with means for readily closing the opening when the device is not in use.

15 Another object is to provide a tooth brush powder container into which a tooth brush may be inserted, which may readily be opened for cleaning.

A further object is to provide a tooth powder applicator by which powder may be applied to a tooth brush by inserting the tooth brush therein, which is provided with means indicating by "feel" from the exterior of the device when the device is closed.

25 A still further object of the invention is to provide a small unique tooth powder applicator which is of a comparatively simple and economical construction.

With these ends in view, the invention embodies a powder container in the form of a shell, closed at one end, open at the other, having an elongated opening in one side, and a filling spout; and an inner shell also closed at one end and open at the other, and also provided with an elongated opening adapted to register with the elongated opening of the container and also adapted to register with the said filling spout.

For a full and more complete understanding of the invention, reference may be had to the following description and accompanying drawing, wherein:

Figure 1 is a perspective view showing the container.

Figure 2 illustrates the container with the elements separated, and with parts shown in elevation and parts in section.

Figure 3 is a view showing the container partly separated and showing the elongated opening through which a tooth brush may be inserted.

reference characters denote corresponding parts. A container 10 is formed with a closure 11 at one end, a spout 12 at one side, and an elongated opening 13 in the opposite side. An inner shell 14, having a closure 15 at one end and an elongated

gated opening 16 in one side, to correspond with the opening 13, is inserted in the open end of the container 10, providing a closure for the open end and also providing means for closing the spout 12 and opening 13 when the opening 16 is positioned between the openings 12 and 13.

Figure 3 illustrates the relative positions of the openings and it will be noted that with the shell 14 in the container 10 the opening 16 may register with the opening 13 and at this time the wall of the inner shell will cover and close the spout 12. The end 15 of the inner shell is knurled and may readily be turned to such position that the opening 16 will register with the spout 12 and with the inner shell in this position the wall thereof will close the opening 13. Powder may be placed in the container with the inner shell in this position by inserting the spout 12 in the opening at the end of a powder container and turning the powder container upside down or so that powder may run therefrom through the spout into the container 10. The inner member 14 may then be turned to close the spout opening and, with the opening 16 between the spout 12 and the opening 13, wherein it will not register with either, the container will be closed.

The open or inner end of the shell 14 may be provided with projections 17 that may snap into recesses 18 in the inner surface of the container 10 to indicate the different positions, such as filling, using and closing of one element in relation to the other. These projections also provide holding means for holding the inner shell in the container. The walls of the inner shell may be tapered slightly to facilitate inserting the open end in the container, the projections 17 necessarily causing slight compression or contraction of the open end until they snap into the recesses 18.

The end 15 of the inner shell may also be provided with a notch 19 to register with indicating means on the surface of the container 10, such as a line 20 with the word "close" for indicating the closed position, or the notch may be turned to register with a line 21 to indicate the position for "use" wherein a tooth brush may be inserted through the opening, and other lines such as a line or mark with the word "fill" may also be provided for indicating the position of the inner shell when the spout is open.

The construction of the device will be readily understood from the foregoing description. In use the container may be filled or partly filled with tooth powder, as described, and may ordinarily be kept in a cabinet in the bath room and used as desired or may be carried on week-end trips so that the necessity of taking the usual can of tooth powder is obviated. The device, therefore, provides means of storing and using tooth powder wherein the powder may readily be applied to the brush without dumping powder thereon.

While a preferred specific embodiment of the invention is hereinbefore set forth, it is to be clearly understood that the invention is not to be limited to the exact construction illustrated and described because various modifications of these details may be provided in putting the invention into practice within the purview of the appended claims.

What is claimed is:

1. A tooth powder applicator comprising a cylindrical container with one end closed and the other open, said container having an elongated

slot in one side adapted to receive the bristles of a tooth brush, a filling spout secured to said container and at a point removed from said slot, said spout having converging sides with a comparatively small outer end and adapted for inserting in an outlet opening of a tooth powder container, and an inner cylindrical shell slideable in said container, said shell having one end closed and the other end open and also having an elongated slot adapted to register with the elongated slot of the container and with the spout, said inner cylindrical shell being disposed in said container with its closed end at the open end of the container and its open end at the closed end of the container.

2. A tooth powder applicator comprising a cylindrical container with one end closed and the other open, said container having recesses formed in the periphery thereof and an elongated slot in one side adapted to receive the bristles of a tooth brush, a conical filling spout secured to said container and at a point removed from said slot, an inner cylindrical shell slideable in said container, said shell having one end closed and the other open and also having an elongated slot adapted to register with the elongated slot of the container and with the spout, and projections on said inner shell, said projections being adapted to snap into said recesses in order to hold the inner shell to the container in a plurality of operative positions, said inner cylindrical shell being disposed in said container with its closed end at the open end of the container and its open end at the closed end of the container.

3. A tooth powder applicator comprising a cylindrical container with one end closed and the other open, said container having recesses formed in the periphery thereof and an elongated slot in one side adapted to receive the bristles of a tooth brush,

4. A tooth powder applicator comprising a cylindrical container with one end closed and the other open, said container having recesses formed in the periphery thereof and an elongated slot in one side adapted to receive the bristles of a tooth brush, a conical filling spout secured to said container and at a point removed from said slot, an inner cylindrical shell slideable in said container, said shell having one end closed and the other open and also having an elongated slot adapted to register with the elongated slot of the container and with the spout, and projections on said inner shell, said projections being adapted to snap into said recesses in order to hold the inner shell to the container in a plurality of operative positions, said inner shell having indicating means registering with said mark on the container designating the said operative positions, said inner cylindrical shell being disposed in said container with its closed end at the open end of the container and its open end at the closed end of the container.
